UNITED STATES PATENT OFFICE.

GEORGE WILLIAM NAHUIS, OF CLEVELAND, OHIO.

DESIGN FOR A COMBINED BUBBLING AND DRAFT FOUNTAIN.

43,010.

Specification for Design.

Patented Sept. 10, 1912.

Application filed June 13, 1912. Serial No. 703,568. Term of patent 7 years.

To all whom it may concern:

Be it known that I, GEORGE WILLIAM NAHUIS, a citizen of the United States, residing at Cleveland, county of Cuyahoga, and State of Ohio, have invented a new, original, and ornamental Design for a Combined Bubbling and Draft Fountain, of which the following is a specification, reference being made to the accompanying drawings, forming part thereof.

In the accompanying drawings Figure 1 is a side elevation of the fountain; Fig. 2

is a plan view of the same, and Fig. 3 is an end view thereof; showing my new design from three points of view.

I claim—

The ornamental design for a combined bubbling and draft fountain, as shown.

In testimony whereof I hereunto set my hand this 29th day of May, 1912.

GEORGE WILLIAM NAHUIS.
